STAPLING DEVICE

Frank R. Curtiss, New Haven, Conn.

Application January 21, 1953, Serial No. 332,232

8 Claims. (Cl. 1-3)

1

This invention relates to stapling devices and more particularly to means for facilitating the insertion of staples into the staple magazine.

Heretofore in stapling devices, a staple magazine was provided and a staple pusher was inserted in the magazine to urge the staples in the magazine into stapling position. Many efforts have been made to provide a means by which the staples can be readily inserted as, for example, by providing the pusher with a fingerpiece whereby it can be removed from the rear open end of the magazine, but this usually requires substantial handling of the pusher in moving it out of and back into the magazine. Also pushers of this type are usually urged forward by a flat, wound spring which when flexed to move the pusher out of the magazine tends to fatigue and break.

The present invention overcomes these difficulties by providing a structure which is simple to operate, may be quickly actuated, and which leaves the operator's hands free to insert the sticks of staples into the magazine.

In carrying out the present invention a member, which may also form the cover for the magazine, is pivoted adjacent the forward end of the arm having the magazine for movement toward and away from the arm. The member is so constructed that it carries the staple pusher and the means urging the staple pusher for movement therewith and is provided with means for latching the staple pusher in a retracted position and the member in covering position, which latter means may be released to permit the member and pusher to be moved away together from the magazine to afford easy access to the rear open end of the magazine for the insertion of the staples.

A feature of the invention resides in the fact that the staple pushing means, being connected to the member or cover which is swung away to afford access to the open rear end of the magazine, is automatically removed from the magazine thus freeing the operator's hands from the necessity of holding or handling the staple pusher during the loading of the magazine and yet having it in ready position to be returned to assume its pushing operation upon return of the member to position overlying the arm.

Another feature of the invention resides in

2

the fact that the means for urging the pusher is mounted on the member for movement therewith so that there is no occasion to flex the same and cause fatigue.

Another feature of the invention resides in the simple, yet effective construction of the parts and their operation.

Other features and advantages of the invention will be apparent from the specification and claims when considered in connection with the drawings in which:

Figure 1 shows a side view partly in section of the device of the present invention.

Fig. 2 is a top view of the device.

Fig. 3 is a sectional view taken along lines 3-3 of Fig. 1.

Fig. 4 is a sectional view of the arm taken along lines 4-4 of Fig. 1.

The stapling device of the present invention may be used for many purposes and in many organizations but is particularly adapted for a construction in which the stapling device is suspended from a support.

As shown in the drawings, the device comprises a base 10 having keyholes 11 whereby it may be suspended on a vertical supporting surface (not shown). Pivotally connected to the rear end of the base is an arm 12 to extend downwardly over the base and urged by spring

13 into the raised position shown in Fig. 1 in which it is stopped by stop member 14. The arm, as shown in Figs. 1 and 4, has a staple magazine formed therein by a U-shaped passage

15 extending therethrough and providing a staple supporting core 16 to receive and support sticks of inverted U-shaped staples S. The magazine is open at the rear end for the insertion of staples and terminates at its forward end adjacent a staple driving means 17 carried

by a staple driving head 18 formed at the forward end of the arm. If desired, staple guiding members 19, Fig. 3, may be provided on the arm to overlie the top edges of the staples and prevent the stick of staples from buckling as they are being fed into staple driving position.

Disposed in the staple passage to the rear of the stick of staples is a U-shaped staple pusher 20 which, according to the present invention, is carried by a member 21 overlying the arm. This member may take many forms but in the present

form of the invention it extends over the arm and in addition forms a hollow cover therefor. A feature of the present invention resides in the pivoting of the member adjacent the forward end of the arm for movement to and from the position overlying the arm as shown in Fig. 1. While the member may be pivoted in any manner, it is herein illustrated as being mounted on the stapling head by an offset pivot means 22 connected to an extension 21a of the cover.

In mounting the pusher on the cover for movement therewith, it is at present preferred to provide an elongate rod 23 located within the cover passing through an aperture 20a in a manipulating finger 20b connected to and projecting upwardly from the staple pusher. The finger projects upwardly above the cover through a longitudinal slot 21b in the cover to enable the staple pusher to move longitudinally therewith and along the magazine.

The pusher is urged forwardly to feed the staples in the magazine to staple driving position by urging means carried by and movable with the cover. In the illustrated form of the invention this comprises a coil spring 24 surrounding the rod in back of the pusher so as to normally urge the pusher member forwardly and position the staples in staple driving position wherein the staple driving means forces the staple through the work (not shown) and into engagement with the staple turning means 10a formed in the base. Since the spring urging the pusher moves with the cover, it is not flexed during each replenishment of the magazine and hence does not become fatigued and broken.

In accordance with the present invention a pivoted latch 25 is mounted on the cover adjacent the rear end of the arm and has a portion 25a normally urged by spring 26 into a position to overlie the elongate slot. When the pusher is moved to retracted position by the manipulating finger, the finger will snap past the portion of the latch and upon being released will engage the latch and the pusher will be held in retracted position. Spring 24 will maintain the finger pressed against the latch and an ear 25a on the latch will prevent movement of the latch under urging of the spring 24.

It will be noted in Fig. 3 that the staple guiding members 19 for the magazine terminate inwardly from the rear of the magazine so that when the staple pusher is held by the latch in retracted position it will be located to the rear of the guides and free of the guides so that when the member or cover 21 is moved about its pivot the pusher can readily move with the member out of the magazine.

Normally the cover is held in overlying relation with the arm and against movement about the pivot by releasable latch means. In the illustrated form of the invention the latch means comprises a depending latch member 27 pivotally carried by the cover and having a projecting portion 27a adapted to engage the undersurface of the arm to hold the cover in position. While any suitable spring may be used to urge the latch into cover holding position, it is at present preferred to utilize spring 26 which is connected to latch 25 for this purpose by connecting the opposite end to latch 27 as shown in Fig. 1.

When it is desired to replenish the supply of staples, it is merely necessary to engage the manipulating finger 20b and move the staple pusher to latched retracted position. Latch member 27 is then actuated to move portion 27a

out of engagement with the arm and releasing the cover with the retracted pusher latched in retracted position for movement away from the arm, thus exposing the rear staple receiving opening in the magazine to readily receive staples therein. The cover can pivot completely about its pivot so that it will hang in a depending position if desired, or any suitable stop means, not shown, may be interposed in the path of movement of the member to stop it with the desired opening.

Since the operator does not have to handle the staple pusher during the replenishing operation and the member or cover carrying the pusher is moved away from the arm so that ample room is afforded for the insertion of the staples, the replenishment of the staples in the magazine may be accomplished very quickly and easily.

After a supply of staples has been inserted in a magazine, it is merely necessary to move the cover back to latched position overlying the arm. In doing so the pusher is automatically positioned in the staple receiving passage so that upon release of the pusher latch the coil spring automatically moves the pusher into engagement with the staples to urge them into staple feeding position.

In order to facilitate the movement of the cover back into overlying relation with the arm, guide means 28 are provided which extend down over the sides of the arm and guide the cover into proper relation therewith as it is swung about its pivot.

Thus it will be seen that with the device of the present invention, which can be formed of any suitable material, replenishment of the staple supplies is greatly facilitated.

Variations and modifications may be made within the scope of the claims and portions of the improvements may be used without others.

I claim:

1. In a stapling device having an arm provided with a rear opening staple magazine to receive and hold a supply of staples therein and a staple driving means adjacent the forward end, and a staple pusher positioned in said magazine and urged forwardly therein to feed staples to said staple driving means; the improvement wherein a rearwardly extending member is pivotally carried by the arm and is movable about said pivot to and from a position overlying the arm; means on the pusher for moving the pusher to retracted position; means on the member for engaging and releasably holding the pusher in retracted position for movement with said member and out of the magazine; and means releasably holding the member in position overlying the arm, said means being released to permit movement of the member and retracted pusher about the pivot away from the arm to expose the rear staple receiving opening in the magazine to readily receive staples therein.

2. In a stapling device having an arm provided with a rear opening staple magazine to receive and hold a supply of staples therein and a staple driving means adjacent the forward end; the improvement wherein a member is pivotally carried by the arm and is movable about said pivot to and from a position overlying the arm; a staple feeding pusher mounted on the member for movement therewith and for longitudinal movement therewith, said pusher being adapted to be positioned in the magazine to engage the supply of staples therein; means mounted on the member for urging the pusher forwardly to feed the staples

to the staple driving means; means on the pusher for moving the pusher to retracted position; means on the member for engaging and releasably holding the pusher in retracted position; and means releasably holding the member in position overlying the arm, said means being released to permit movement of the member and retracted pusher away from the arm to expose the rear staple receiving opening in the magazine to readily receive staples therein.

3. In a stapling device having an arm provided with a rear opening staple magazine to receive and hold a supply of staples therein and a staple driving means adjacent the forward end, said magazine having guiding means overlying the staples and terminating inwardly from the rear end of the arm; the improvement wherein a member is pivotally carried by the arm and is movable about said pivot to and from a position overlying the arm; a staple feeding pusher mounted on the member for movement therewith and for longitudinal movement therealong, said pusher being adapted to be positioned in the magazine to engage the supply of staples therein; means mounted on the member for urging the pusher forwardly to feed the staples to the staple driving means; means on the pusher for moving the pusher to retracted position; means on the member for engaging and releasably holding the pusher in retracted position to the rear of the end of and free from said guiding means; and means releasably holding the member in position overlying the arm, said means being released to permit movement of the member and retracted pusher away from the arm to expose the rear staple receiving opening in the magazine to readily receive staples therein.

4. In a stapling device having an arm provided with a rear opening staple magazine to receive and hold staples therein and a staple driving head at the forward end provided with staple driving means, and a pusher positioned in the magazine to engage the staples and feed them to a position to be driven by the staple driving means; the improvement wherein a member is pivotally mounted adjacent the forward end of said arm and is movable about said pivot to and from a position overlying the arm; means mounting the pusher on the member for movement therewith and for longitudinal movement therealong; a coil spring carried by the member for movement therewith and engaging and urging the pusher forwardly to feed the staples in the magazine; means on the pusher for moving the pusher to retracted position; a spring pressed latch on the member for engaging and releasably holding the pusher in retracted position against the urging of the coil spring; and a spring pressed latch on the member engaging the arm and holding the member in position overlying the arm and upon being released enabling the member and latched pusher to be moved away from the arm to expose the rear staple receiving opening in the magazine to readily receive staples therein.

5. In a stapling device having an arm provided with a rear opening staple magazine to receive and hold staples therein and a staple driving head at the forward end provided with staple driving means, and a pusher positioned in the magazine to engage the staples and feed them to a position to be driven by the staple driving means; the improvement wherein a cover is pivotally mounted adjacent the forward end of said arm and is movable about said pivot to and from

a position overlying the arm; means mounting the pusher on the cover for movement therewith and for longitudinal movement therealong; means mounted on the cover for urging the pusher forwardly to feed the staples in the magazine; means on the pusher for moving the pusher to retracted position; means on the cover for engaging and releasably holding the pusher in retracted position; and means releasably holding the cover in position overlying the arm, said means being released to permit movement of the member and retracted pusher away from the arm to expose the rear staple receiving opening in the magazine to readily receive staples therein.

6. In a stapling device having an arm provided with a rear opening staple magazine to receive and hold staples therein and a staple driving head at the forward end provided with staple driving means, and a pusher positioned in the magazine to engage the staples and feed them to a position to be driven by the staple driving means; the improvement wherein a cover is pivotally mounted adjacent the forward end of said arm and is movable about said pivot to and from a position overlying the arm; an elongate rod within the cover for mounting the pusher on the cover for movement therewith and for longitudinal movement therealong; a coil spring surrounding said rod for engaging and urging the pusher forwardly to feed the staples in the magazine; means on the pusher for moving the pusher to retracted position; means on the cover for engaging and releasably holding the pusher in retracted position against the urging of said coil spring; and means releasably holding the cover in position overlying the arm, said means being released to permit movement of the member and retracted pusher away from the arm to expose the rear staple receiving opening in the magazine to readily receive staples therein.

7. In a stapling device having an arm provided with a rear opening stapling magazine to receive and hold staples therein and a staple driving head at the forward end provided with staple driving means, and a pusher positioned in the magazine to engage the staples and feed them to a position to be driven by the staple driving means, said pusher having a manipulating finger; the improvement wherein a cover is pivotally mounted adjacent the forward end of said arm and is movable about said pivot to and from a position overlying the arm; means mounting the pusher on the cover for movement therewith and for longitudinal movement therealong, said cover having a longitudinal slot therein through which the manipulating finger projects for movement of the pusher to retracted position; means mounted on the cover for urging the pusher forwardly to feed the staples in the magazine; latch means on the cover for engaging the manipulating finger and releasably holding the pusher in retracted position; and means releasably holding the cover in position overlying the arm and upon being released enabling the cover and pusher to be moved away from the arm to expose the rear staple receiving opening in the magazine to readily receive staples therein.

8. In a stapling device having a base, an arm pivotally mounted on the base adjacent the rear end and having a rear opening staple magazine provided with staple guides to receive and hold staples therein and a staple driving head at the forward end provided with staple driving means, and a pusher positioned in the magazine to move under said guides to engage the staples and feed

them to a position to be driven by the staple driving means; the improvement wherein a cover is pivoted to the staple driving head and extends rearwardly therefrom and is movable about said pivot to and from a position overlying the arm; means mounting the pusher on the cover for movement therewith and for longitudinal movement therealong, the guides on said magazine terminating inwardly of the rear end of the magazine for releasing the pusher from the magazine for movement with the cover; means mounted on the cover for urging the pusher forwardly to feed the staples; means on the pusher for moving the pusher to retracted position; means on the cover for engaging and latching the pusher in a 15

5

retracted position; and means releasably latching the cover in position overlying the arm, said means being released to permit movement of the member and retracted pusher away from the arm to expose the rear staple receiving opening in the magazine to readily receive staples therein.
